The ornamental design for a toilet odor removal device, as shown and described.

DESCRIPTION

In FIG. 1, the broken line showing of a conventional toilet is for illustrative purposes only and forms no part of the claimed design. Additionally, in FIGS. 1, 2 and 4 the cord of the device is shown broken away to indicate indeterminate length.

FIG. 1 is a front elevational view of the toilet odor removal device showing my new design;

FIG. 2 is a rear elevational view thereof;

FIG. 3 is a right side elevational view thereof;

FIG. 4 is a left side elevational view thereof;

FIG. 5 is a top plan view thereof; and,

FIG. 6 is a bottom plan view thereof.
